UNITED STATES PATENT OFFICE.

CHARLES F. HOPEWELL, OF WATERTOWN, MASSACHUSETTS, ASSIGNOR TO HOPEWELL BROTHERS, OF WATERTOWN, MASSACHUSETTS, A COPARTNERSHIP COMPOSED OF CHARLES F. HOPEWELL AND HELEN C. HOPEWELL.

WINDSHIELD VISOR.

Application filed September 8, 1920. Serial No. 408,965.

To all whom it may concern:

Be it known that I, CHARLES F. HOPEWELL, a citizen of the United States, and resident of Watertown, county of Middlesex, State of Massachusetts, have invented an Improvement in Windshield Visors, of which the following description, in connection with the accompanying drawing, is a specification, like characters on the drawing 10 representing like parts.

This invention relates to improvements in wind-shield visors and other devices comprising a frame which is pivotally supported and provided with means for securing the 15 frame in different positions of angular adjustment relatively to the support.

In usual constructions of this character the frame is provided with a member which is pivotally supported in brackets, or in suitable bearings, and clamping means, carried by the ends of the pivotal member, are clamped against the brackets to secure the frame in adjusted positions. In such constructions a tension or a strain is imposed 25 upon the bracket which is likely to loosen the bracket eventually, particularly if the pivotal members are not provided with shoulders adapted to abut against the inner face of the bracket, or even when such shoulders are provided, if the brackets are not 30 located with the greatest accuracy.

One of the objects of the present invention is to produce a clamping means for a wind-shield visor, or similar device, which will not 35 impose any lateral strain upon the bracket or other supporting means and which will not necessitate such accurate positioning of the bracket.

Another object of the invention is to provide a supporting means for a device of the character described which will enable the same to be easily assembled upon the support or dismantled therefrom.

A further object of the invention is to 45 provide a frame for wind-shield visors, and like constructions, in which the parts can be more readily assembled than in constructions heretofore made.

Other objects and features of the invention will more fully appear from the following description and the accompanying draw-

ings and will be pointed out in the annexed claims.

A preferred embodiment of the invention is illustrated herein as applied to the windshield visor of an automobile, but it will be understood that the invention is of broader application and is adapted to be employed in connection with various other devices.

In the drawings:

Fig. 1 is a view of the front portion of an automobile showing a visor, embodying my invention, applied thereto,

Fig. 2 is a detail view of a portion of the front wall of a closed car illustrating my invention applied thereto,

Fig. 3 is a view showing my invention as applied to a visor for an open car,

Fig. 4 is a detail view, mainly in horizontal axial section, of the pivotal member of 70 the visor frame and support illustrated in Fig. 2,

Fig. 5 is a detail view of a supporting bracket, showing in section means by which the pivotal member of the frame is supported therein, and,

Fig. 6 is a detail view illustrating another type of supporting bracket embodying my invention.

Fig. 7 is a perspective view of another 80 type of bracket embodying my invention.

The invention is disclosed herein as applied to the visor 1 of an automobile which comprises a rectangular frame having means for pivotally securing the same to the front 85 wall of an automobile, or to the front rib 2 of the top of the automobile as illustrated in Fig. 1, means being provided for clamping the visor in any desired position of adjustment around its pivotal support so that 90 the eyes of the operator will be protected from the glare of the sunlight, the visor also serving to prevent rain from striking the upper portion of the wind-shield.

In the preferred embodiment of my invention the visor comprises a rectangular frame consisting of parallel arms 3 and 4 which are secured together at their front ends by a rod 5 preferably having screw threaded connections 6 to the ends of the arms 3 and 4 and a rear extensible, pivotal member which preferably is in the form of a sec-

tional rod the ends of which are pivotally mounted in suitable supporting brackets which are secured to the front wall of the car if a closed car, or to the front bow of the 5 top if used upon an open car.

The extensible rod illustrated herein comprises a section 7 which is provided with means for pivotally supporting it at the end and a short section 8 which is provided with 10 similar means for pivotally supporting it in suitable journals in the brackets, the adjacent ends of the sections 7 and 8 being provided with interlocking means which will permit said sections to be extended axially, 15 but which will prevent their rotation relatively to each other. A convenient means, which is illustrated in Fig. 4, consists in cutting away from each section one-half of its diameter for a short distance from the 20 end adjacent the other section and overlapping the sections so that one will slide axially relatively to the other, the joint thus formed being enclosed in a suitable sleeve 9. The end of each section desirably is secured 25 by a pin 10, or otherwise, to a hub upon the arm 3 or 4 which forms the side of the frame adjacent the end of such section. The end of each of the sections 7 and 8 of the pivotal supporting rod is extended beyond the arm 30 3 or 4 a sufficient distance to pass through suitable journals in a supporting bracket, such end being provided with screw threads 11, adapted to be engaged by a suitable clamping nut which, in co-operation with the 35 face of a shoulder 12 upon the arm 3 or 4, will firmly clamp upon the bracket with sufficient force to retain the frame in any adjusted position. By reason of the extensibility of the rod the clamping action thus 40 afforded produces no lateral strain or tension upon the supporting bracket and consequently there is no tendency of the clamping means to pull the bracket from its support.

45 Furthermore, by providing a sectional supporting member of this character the frame is much more easily assembled since the front rod 5 may be screwed at one end into the member 4 of the frame and the other 50 arm 3 then screwed upon the opposite end of the rod 5 before the sections 7 and 8 of the pivotal supporting member are assembled.

A further feature of the invention consists in providing a convenient means for detachably securing the windshield visor frame to the brackets upon the car. This is accomplished by forming in one or both brackets an open slot leading to the journal 55 for the supporting member of the frame and in providing suitable removable means for closing said slot to retain said supporting member therein. In the preferred construction illustrated herein each of the brackets 60 is provided with a journal 13 of consider-

ably greater diameter than the diameter of the end portions 11 of the pivotal supporting members or rod sections 7, 8, and a clamping nut 14 is employed having an extension or hub 15 which fits the journal 13 in the 70 bracket.

The lower portion of the bracket is provided with a slot 16 slightly broader than the diameter of the end portions 11 of the pivotal member of the frame. By reason of 75 this construction the nut 14 can be backed off sufficiently from each end of the pivotal supporting member to withdraw the hub 15 from the journal 13 so that the ends 11 of the pivotal supporting member or rod can be 80 removed through the slots 16. By a reverse operation the visor can be readily replaced upon the car when needed. Such a construction is particularly desirable for use in connection with open cars since it is necessary or desirable to remove the visor from the top if the latter is to be folded back. In such case the visor, after having been removed, may be placed within the slip cover 85 for the folded top.

90 Any suitable means may be provided for securing the bracket to the car. In Figs. 2 and 4 the bracket is shown as provided with a base 17 which is secured to the front wall of a closed car by suitable screws. In Fig. 95 3 a bracket is illustrated which is adapted to be secured to the front bow of an open car, the bracket comprising a base 18 having a flange 19 extending upwardly from one edge thereof, screws 20 and 21 passing through the base 18 and flange 19 respectively into the front rib of the top. Since these screws extend into the rib at right angles to each other a very firm anchorage is provided for the supporting bracket.

100 In Fig. 6 a different form of bracket is shown in which the body portion 22 of the bracket is provided with parallel extensions 23 and 24 which are adapted to embrace a supporting member 25, the bracket being 110 clamped thereon by one or more set screws 26 which pass through one or both of the extensions 23 and 24. In this construction, as in the other, the journal for the pivotal supporting member is considerably larger 115 than the end of said supporting member to receive the hub of the clamping nut which secures the frame in adjusted position.

120 A further embodiment of my invention is illustrated in Fig. 7 which, as illustrated, 120 comprises a bracket having a base 28 provided with ears 29 which support a pintle 30 upon which an extension 31 of the frame-supporting member 32 is mounted. The frame-supporting member is provided with 125 a journal 33 to receive the rod or pintle member of the frame. An open slot 34 leading to the journal 33 provides means by which the rod or supporting member may be introduced into the journal. Any suit- 130

able means may be provided for retaining the supporting member of the frame in the journal, such for example, as a hub upon the clamping nut heretofore described, or 5 other removable means which will serve to close the slot and retain the pivotal supporting member of the frame therein.

By thus pivoting the member of the bracket, which contains the journal for the 10 supporting member, relative movement is permitted between the bracket and the member which is journalled in it which permits the supporting member to be clamped against the bracket without imposing any 15 lateral strain upon the bracket which would tend to loosen it from its anchorage.

It will be understood that the embodiment 20 of the invention disclosed herein is illustrative and not restrictive, and that various other forms of construction and arrangement of parts may be made within the spirit and scope of the following claims and that the invention is adapted to various other purposes than those herein specifically mentioned.

Having thus described my invention, what I claim as new, and desire to secure by Letters Patent, is:

1. A device of the class described comprising supporting brackets, a rectangular frame having an extensible rod formed in interlocking sections rotatably mounted in said supporting brackets and a shouldered collar secured to one end of said extensible 30 rod engaging the inner side of one of said brackets and clamping means on said extensible rod engaging the other side of said bracket.

2. A device of the class described comprising a frame having one side provided with an axially extensible rod formed in sections having interlocking adjacent ends, supporting brackets having journals and provided with open slots leading to said 40 journal to permit the introduction of said rod into said journal, and nuts on the ends of said rod having hubs fitting said journals.

3. A device of the class described comprising a frame having one side formed of a 50 rod made in sections having interlocking adjacent ends and removable axially relatively to each other, and side arms fixedly secured to the respective sections of said rods, supporting brackets for the ends of said 55 rod sections having journals and provided with slots to permit the introduction of said rod into said journal and nuts on said rod having hubs fitting said journals operable to clamp said arms against said 60 brackets.

4. A device of the class described comprising a frame having one side formed of a rod made in sections having interlocking adjacent ends and removable axially relatively to each other, a sleeve enclosing said 65 adjacent ends, side arms fixedly secured to the respective sections of said rod, one of said arms being pinned to said sleeve and rod, supporting brackets for said rod having 70 journals and provided with slots to permit the introduction of said rod into said journal, and nuts on said rod having hubs fitting said journals operable to clamp said arms against said brackets.

5. A device of the class described comprising a rectangular frame comprising a supporting rod and side members having eyes embracing said rod, a pair of brackets each having a journal and a 80 relatively small open-ended slot leading to said journal to permit the introduction of said supporting rod, into said journal, nuts on said supporting rod having hubs fitting said journals, for clamping said side members against said brackets and means operable to permit a relative movement of one end of the supporting rod and the bracket in the direction of the axis of the supporting rod to enable a proper clamping action 85 to be obtained notwithstanding inaccurate positioning of the bracket in respect to the normal length of the rod.

In testimony whereof, I have signed my name to this specification.

CHARLES F. HOPEWELL.
